UNITED STATES PATENT OFFICE.

THOMAS HAWKINS, OF DERRY, NEW HAMPSHIRE, ASSIGNOR TO W. B. SEVERANCE,
OF MANCHESTER, NEW HAMPSHIRE.

SORTING-RACK.

1,398,778.

Specification of Letters Patent. Patented Nov. 29, 1921.

Application filed March 18, 1921. Serial No. 453,200.

To all whom it may concern:

Be it known that I, THOMAS HAWKINS, a citizen of the United States, and a resident of Derry, in the county of Rockingham and 5 State of New Hampshire, have invented a new and Improved Sorting-Rack, of which the following is a full, clear, and exact description.

This invention relates to improvements in 10 sorting racks, an object of the invention being to provide a sorting rack for letters, which will expedite the work of mail carriers in arranging letters delivered on their respective routes.

15 A further object is to provide a rack of the character described, which will be simple and practical in construction, strong and durable in use, and comparatively inexpensive to manufacture.

20 With these and other objects in view, the invention consists in certain novel features of construction and combinations and arrangements of parts as will be more fully hereinafter described and pointed out in the 25 claims.

In the accompanying drawings:—

Figure 1 is a perspective view of my improved rack;

Fig. 2 is a fragmentary view in section 30 therethrough on the line 2—2 of Fig. 1;

Fig. 3 is a similar view in section on the line 3—3 of Fig. 1, with the fingers 6 moved to inoperative position to permit the removal of the mail matter from the rack; 35 and

Fig. 4 is an enlarged view in section through one of the shafts 5.

Referring in detail to the drawings, 1 represents a desk or table, supported upon legs 40 2 and serving to support a sorting rack 3. The rack 3 is in the form of a rectangular box having an open front and being provided with a plurality of shelves 4. It is customary to provide a plurality of partitions to divide the spaces between the shelves into a number of pigeon holes and to sort the mail matter into the pigeon holes. With this form of rack, it is of course necessary to remove the mail matter from one pigeon 45 hole at a time after it has been sorted.

I provide a rack which is sub-divided into any desired number of compartments to take the place of pigeon holes and in which the partitions between the compartments 50 may be simultaneously and quickly swung

out of the way after the mail has been sorted and permit an entire shelf of mail to be removed from the rack at one time.

Referring now to the specific construction, a crank shaft 5 is mounted above and 60 parallel to each of the shelves 4. A plurality of parallel crank fingers such as 6 are rigidly connected to each shaft 5 and depend therefrom dividing each shelf into a number of compartments in which the mail matter 65 may be sorted.

The shafts 5 extend through one end of the casing, and crank arms 7 are fixed thereto. One of the crank arms 7 is provided with an extension 8 forming a handle and 70 all of the crank arms are connected by a link 9 to compel simultaneous movement of all of the fingers 6 when the handle 8 is operated. The handle 8 and the crank arm to which it is attached form an operating 75 lever. A spring held locking tongue 9 operated by a handle member 10 pivoted on the lever is selectively engageable in the notches of a notched sector bar 11, secured to the outer face of the rack. It will thus 80 be seen that the fingers 6 may be locked in the position illustrated in Figs. 1 and 2, while the mail is being sorted and then swung upwardly and locked in the position illustrated in Fig. 3 to facilitate and expedite the removal of the sorted mail from 85 the rack.

I have illustrated one of the preferred embodiments of my invention, but it will be apparent that various slight changes and alterations might be made in the general form and arrangement of the parts described without departing from the invention and hence I do not wish to limit myself to the precise details set forth, but shall consider myself at liberty to make such slight changes and alterations as fairly fall within the spirit and scope of the appended claims. 90

I claim:—

1. In a sorting rack, a plurality of shelves, 100 crank shafts located above the shelves, depending crank fingers carried by the shafts and dividing the shelves into compartments, means for simultaneously swinging all of said fingers to inoperative position to facilitate the removal of the sorted matter from the shelves, said means comprising crank arms carried by the shafts, a link compelling all of said crank arms to move together, a lever forming a continuation of one of said 105 110

crank arms and controlling the position of the link.

2. In a sorting rack, a plurality of shelves, crank shafts located above the shelves, depending crank fingers carried by the shafts and dividing the shelves into compartments, means for simultaneously swinging all of said fingers to inoperative position to facilitate the removal of the sorted matter from

the shelves, said means comprising crank arms carried by the shafts, a link compelling all of said crank arms to move together, a lever controlling the position of the link, a notched sector bar, a spring held device carried by the lever and selectively engageable with the notches in the bar to lock the fingers against movement.

THOMAS HAWKINS.
